UNITED STATES PATENT OFFICE.

EDGAR F. HATHAWAY, OF WELLESLEY, MASSACHUSETTS, ASSIGNOR TO SHAWMUT ENGINEERING COMPANY, OF BOSTON, MASSACHUSETTS, A CORPORATION OF MASSACHUSETTS.

TUBE FRAME FOR TUFT WEAVING.

Application filed July 20, 1923. Serial No. 652,727.

This invention relates to tube frames used in weaving tufted fabrics such as Axminster carpets, and is intended to provide means for detachably securing the tuft tubes to the longitudinal carrier bar forming the back bone of the tube frame that will preserve perfect alignment and parallelism of the tuft tubes against the ordinary stresses of service, while making it possible 10 to remove injured tubes and replace them with others without withdrawing the tube frame from the loom.

The present invention is particularly applicable for use in cases where it is desired 15 for special reasons to locate the tuft tubes with their intake ends positioned near the lower edge of the carrier bar, and yet not leave the delivery ends projecting an unnecessary distance below the lower edge or 20 bottom of the bar.

A leading feature of the invention consists in the combination with the longitudinal carrier bar, of a series of parallel tuft tubes detachably secured thereto by a telescopic connection which allows the tuft 25 tubes to be attached or detached by sliding them longitudinally of the bar into or out of their proper positions for use. These and other features will be explained in the 30 following specification and will be defined in the claims hereto annexed.

In the accompanying drawings I have illustrated different forms of construction and arrangement embodying the principles 35 of this invention, in which:

Figure 1 is a front elevation showing the complete tube frame embodying my improvements with the middle portion broken away.

Figure 2 is a transverse section through the carrier bar showing the interlocking connection with the individual tuft tubes.

Figure 3 is a perspective of the parts shown in Figure 2 in disassembled position.

Figure 4 is a longitudinal section illustrating the interlocking assemblage of the tuft tubes with the carrier bar.

Figure 5 is a cross section of a slightly modified form of the invention.

Figure 6 is a perspective view of the parts shown in Figure 5 in disassembled relation.

In the practice of the invention, as illustrated in the drawings, the longitudinal car-

rier bar 1, is made in hollow form of sheet metal and comprises a hollow truss or channel comprising a back wall 2, top wall 3 and a bottom wall 4, adapted to be secured over the inwardly projecting vertical attaching lips or flanges 5, by which the carrier bar is secured to the hanger 6, which is provided with an upwardly extending chain-engaging tongue 7, and a movable hook arm 8, cooperating therewith to suspend the hanger from the carrier chain in a well known manner. The yarn spool, not shown, is mounted in the bearing ears or brackets 9, so as to be supported in parallelism with the carrier bar 1, with its yarn ends carried through the individual tuft-guiding tubes 10, by which the yarn tufts are properly presented to the fabric being woven in the loom.

The main element or channel of the carrier bar has its top and bottom walls bent back to form reversely turned lips or flanges 3^a and 4^a, which form part of the interlocking connection by which the tuft tubes are detachably secured to the carrier bar.

The individual tuft tubes 10 are soldered side by side in parallelism with their opposite ends aligned with one another to a suitable holding strip 12, whose opposite edges are reversely bent to form interlocking flanges 12^a and 12^b, dimensioned to form a telescoping engagement with the corresponding flanges 3^a and 4^a, of the main element or channel of the carrier bar construction.

In order to protect the in-feeding yarn tufts from chafing against the sharp rearward edges of the intake openings of the tuft tubes, the main body portion of the bar 12 has its upper portion somewhat offset or outwardly bulged, as shown at 12°, to raise this portion of its surface beyond the level of the adjacent back edges of the tuft tubes so that the yarn does not come in contact with or scrape against the back edges of the tubes.

As shown in the drawings, the end of the tube-carrying element or strip 12 may be formed with inwardly offset lips or flanges 12^a which lap under the adjacent edge of the next unit or section of the tube-attaching element 12.

The main carrier bar element is made integral of the required length for the tube

frame, but the tube-attaching members may be made in shorter sections of any desired length, and in such cases the short flanges 12^a serve to preserve perfect alignment by forming a lapped joint between different adjacent sections.

In practice, the individual tuft tube units or sections are assembled by presenting them with their attaching plate in endwise alignment with the flanged edge portions 3 and 4 of the main carrier bar element, and are then slid along the main carrier bar element with which they have telescoping engagement until the requisite number of tuft tubes are assembled side by side on the carrier bar. To provide against endwise displacement along the carrier bar of the tuft tube sections or units, I provide an anchoring screw 15 which passes through the outwardly projecting end of the plate 12, into the front attaching lip 5 of the hanger. The removal of this screw permits the withdrawal of the end section of the tubes and allows the intermediate sections to be withdrawn thereafter for the purpose of removing any section in which the tubes are injured.

In Figures 5 and 6 I have shown a somewhat modified form of construction in which the carrier bar 20, is made with integral top, bottom and back walls, the bottom wall 20^a, having its forward edge reversely bent to form an attaching flange 20^b, while the top wall is extended and carried over in a forward direction and has its edge reversely infolded as at 20^c, thus leaving a gap between the edge of the integral front wall 20^a and the front edge of the bottom wall to be bridged over by the tube-carrying and attaching strip 21 which has correspondingly turned lips or flanges 22 and 23 for slidably interlocking or telescoping with the flanged edges of the carrier bar 20. The attaching strip 21 also may be provided with an inwardly offset lip 21^a to lap under the adjacent edge of the next section.

What I claim is:

1. A tube frame for tuft weaving embracing in its construction a longitudinal carrier-bar, and a series of parallel tuft-tubes secured thereto to project transversely thereof by an interlocking, slidable, attaching connection which permits the assemblage of the tubes on the bar by a sliding movement longitudinally of the bar, substantially as described.

2. A tube frame for tuft weaving embracing in its construction a longitudinal carrier-bar, and transversely disposed tuft-tubes secured to an attaching member, said member having interlocking attaching connection with said carrier-bar which permits its assemblage and removal by movement longitudinally of the bar, substantially as described.

3. A tube frame for tuft weaving, embracing in its construction a longitudinal carrier bar, transversely disposed tuft tubes and a detachable tube-carrying connecting member formed to have telescoping engagement with the bar longitudinally thereof, and means for preventing longitudinal displacement of said connecting member along the bar when the frame is in use, substantially as described.

4. A tube frame for tuft weaving embracing in its structure a longitudinal carrier-bar provided with longitudinal tube-attaching lips, a series of parallel tuft tubes, a tube-carrying attaching strip constructed to be interlockingly engaged with said lips to detachably retain the tuft tubes in operation position for service, substantially as described.

5. A tube frame for tuft weaving, embracing in its construction a longitudinal carrier bar provided with longitudinal lips, a tube-attaching strip having cooperating lip-engaging members for locking them to said bar and a plurality of parallel tuft tubes secured to said strips, substantially as described.

6. A tube frame for tuft weaving embracing in its construction a longitudinal carrier bar provided with longitudinal hook-like flanges, a tuft-tube attaching strip provided with hook-like members adapted to form interlocking engagement with said flanges, tuft tubes secured on said strip, and means for anchoring said strip against longitudinal displacement along the bar, substantially as described.

7. A tube frame for tuft weaving, embracing in its construction a hollow carrier bar having an open side whose longitudinal edges are bent back to form retaining flanges, a tube-supporting strip whose longitudinal edges are formed to slidably interlock with said flanges, and a row of tuft tubes whose intake ends overlap one side of said strip and are secured thereto, an overhanging portion of said strip being projected outwardly to protect the yarn from chafing against the rear edges of said tubes, substantially as described.

8. A carrier-bar for a tube frame embracing a hollow longitudinal bar and a longitudinal tube-carrying strip detachably secured thereto by a retaining connection permitting the strip to be operatively assembled and to be released by movement lengthwise of the bar, said strip being formed with a longitudinal offset for protecting the tuft yarns against chafing as they enter the tuft tubes, substantially as described.

In witness whereof, I have subscribed the above specification.

EDGAR F. HATHAWAY.
